NECKTIE

Howard L. Cleveland, Hollywood, and Claude A.
Jackson, Los Angeles, Calif.

Application May 28, 1949, Serial No. 2,923

Term of patent 14 years

(Cl. D3—16)

To all whom it may concern:

Be it known that we, Howard L. Cleveland and Claude A. Jackson, citizens of the United States, residing in Hollywood and Los Angeles, respectively, in the county of Los Angeles and State of California, have invented a new, original, and ornamental Design for a Necktie, of which the following is a specification, reference being had to the accompanying drawing, forming part thereof.

Fig. 1 is a partly foreshortened front view of a necktie, showing our new design;

Fig. 2 is a cross-sectional view thereof taken on the line 2—2 of Fig. 1;

Fig. 3 is a front view of the larger end of the necktie as it appears with the box-pleat in opened position, and

Fig. 4 is a plan view of the necktie shown in Fig. 1 drawn on a smaller scale.

The dominant features of the necktie are shown in full lines on the drawing, the same consisting of a normally closed box-pleat that is widest at an intermediate part of the larger end of

the necktie and reducingly tapers at both ends, said box-pleat, when opened, revealing ornamentation applied to the normally hidden portions thereof, are as shown.

We claim:

The ornamental design for a necktie, substantially as shown and described.

HOWARD L. CLEVELAND.
CLAUDE A. JACKSON.
